UNITED STATES PATENT OFFICE.

GEORGE F. LONG, OF NEW YORK, N. Y., ASSIGNOR TO THE G. PIEL COMPANY, INC., A CORPORATION OF NEW YORK.

PEDAL.

1,418,313.

Specification of Letters Patent. Patented June 6, 1922.

Application filed December 31, 1917. Serial No. 209,626.

To all whom it may concern:

Be it known that I, GEORGE F. LONG, a citizen of the United States, and resident of New York city, in the county of Queens and State of New York, have invented certain new and useful Improvements in Pedals, of which the following is a specification.

My invention relates broadly to a pedal actuated control mechanism of general application and particularly designed for moving machine parts against the resistance of strong controlling springs.

In some devices, such as muffler cut-outs of the type usually employed in automobile engine constructions, it is necessary to hold the by-pass controlling gates in closed position by means of strong springs, for otherwise, the heavy engine suction which sometimes, develops in connection with these muffler cut-outs, is of sufficient power to raise the gate into open position. In order to open these gates it is necessary therefore to work against the tension of these heavy holding springs, and in order to develop the necessary operating power when the gates are opened manually, it has been usual to employ a long hand lever. This form of operating device not only detracts from the appearance of the car interior, but requires the operator to remove his hand from the steering wheel in order to actuate the lever. In this way he loses control of the car usually at a time when the control of the steering and power mechanisms is of equal importance with the control of the cut-out.

Accordingly, one of the objects of the invention is to provide a simple, compact form of actuating mechanism capable of developing the necessary actuating power and which may be positioned out of the way underneath the vehicle floor and arranged so as to be actuated by a foot pressure on a small pedal member which extends through the floor convenient to the operator's foot.

Another object of the invention is to provide in such a construction, a locking means for holding the controlled mechanisms in abnormal position, which means are designed to be moved to and from its locking position, simply by kicking the control pedal to one side or the other.

Another object of the invention is to pro-

vide in such a device a simple form of adjustable connection with the cut-out or other mechanism wherever it may be placed relative to the pedal, while maintaining a positive and rigid connection between the pedal and the mechanisms controlled thereby.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings:

Figure 1 is a vertical sectional view through a supporting floor and attaching bracket showing mounted thereon a preferred embodiment of my invention in side elevation;

Figure 2 is a vertical sectional view through one form of mechanism designed to be controlled by the device shown in Figure 1;

Figure 3 is a right end elevational view of the device shown in Figure 1; and

Figure 4 is a plan view showing the devices of Figures 1 and 2 with the control of Figure 1 demounted from its support.

In the drawings, there is shown a flooring 10 which, for the purpose of this disclosure, may be considered as the flooring of an automobile body, and which constitutes a support for the control. It is assumed, for the purpose of this disclosure that the automobile carries at some suitable place thereon a muffler cut-out 11 of any conventional form and spaced from the control mechanism. The muffler cut-out herein illustrated is taken from the United States Patent to 95 Piel No. 1,065,467; granted June 24, 1913, and shows a gate 12 normally held in closed position by a relatively strong spring 13 acting on the gate controlling rod 14. The gate is moved to and from its closed position by means of a lever 15 which extends laterally from and is fixed to the rod 14.

The control mechanism particularly forming the subject matter of this invention includes a bracket 16, the pedal actuated parts 105 carried thereby, together with a rigid reach

rod 17 which has one end pivotally connected to the lever 15 to actuate the same.

The bracket 16 is an L plate with a vertically disposed and depending supporting flange 17' and a horizontally disposed flange 18 designed to engage the underside of the floor 10. The bracket is fastened to the flooring by means of through bolts 19 passing through the flooring and flange 18. If desired, the bolts may be caused to pass through a top plate 20 positioned on top of the flooring 10 opposite the flange 18 thereby to brace the floor therebetween. The top plate 20, flooring 10 and flange 18 are slotted therethrough to provide a vertically disposed opening 21 constituting a guiding means for confining the thrust member 22, hereinafter more fully described, in its vertical reciprocating movement. For convenience in mounting the device in position upon the floor of the vehicle, the portion of the opening 21 extending through the flooring 10 is preferably a straight circular drilling of a diameter equal to the greatest width of the thrust member 22. In this case dependence is placed upon the conformation of the opening in the flange 18 and plate 20 which are fitted to the cross section of the thrust member, so as to provide a two point guiding engagement therewith.

A gear train is mounted on the flange 17' adjacent its lower edge and includes a driving spur gear 23 suitably mounted to revolve about a fixed axis 24 and continuously meshing with a driven spur gear 25 demountably supported upon a stud bolt shaft 26. This bolt extends loosely through the flange 17' and is held in place by the nut 27 engaging the bolt on the rear side of the flange as shown in Figure 3.

A relatively long arm 28 extends radially from the gear 23, has its outer end offset (see Fig. 3) and extends upwardly to the underside of the flange 18 in position slightly offset from the opening 21. The thrust member 22 is a flat steel blade, somewhat L-shaped in side elevation with a horizontally extending projection 29 defining its lower end. This extension constitutes a stop for engaging the underside of the flange 18 to limit the upward movement of the thrust member. The projection is provided with a slot 30 extending lengthwise thereof. A pivot pin 31 connects the outer end of the arm 28 with the slot 30 so as to form a sliding pin and slot connection between the thrust member 22 and the driving gear 23. The upper end of the thrust member 22 is provided with a head 32 for receiving the operator's foot as is usual in pedal constructions. The portion of the thrust member opposite the gear 23 is cut away from the cap end to provide an upwardly facing shoulder 33 which shoulder is adapted to engage under the flange 18, when the pedal is de-

pressed, as shown at dotted lines in Figure 1, thereby to lock the thrust member in its depressed position. When depressed into this locked position the rod 17 is so held that the gate 12 is maintained in open position against the tension of the closing spring 13.

The gear 25 is provided with a relatively short arm 34 integrally extending radially from the periphery thereof and pivotally connected to the end of the rod 17 opposite the end connected to the lever 15.

In operation and with the device mounted in position as shown in Figure 1, the nut 27 on the supporting bolt shaft 26 may be loosened sufficiently to permit the bolt to be shifted until the gear 25 is free to be moved into a position disconnected from its meshing engagement with the gear 23. The rod 17 can then be connected to the muffler lever 15 with the gate 12 either in the fully closed position shown in Figure 2, or in any other desired partially opened position. During this adjustment the gear 25 is rotated freely on the shaft 26 and when the connection with the muffler lever is fixed the gear 25 is moved back into a meshing engagement with the gear 23 and the nut 27 tightened up, thus setting the parts in operative position shown in Figure 1.

Normally the spring 13 re-acts through the rod 17 and the gear train formed by the gear members 25 and 23 to hold the thrust member 22 normally in its fully elevated position.

When it is desired to open the gate 12 the operator steps upon the cap 32 and depresses the thrust member into its lowered position. During this actuation the lever is guided through the opening 21 and swings the arm 28 over an arc which is almost a vertical straight line and acting on the train of gears to convey motion through the reducing gear set to pull the rod 17 in the direction indicated by the arrows in Figures 1 and 2. The parts are so proportioned and disposed that the arm 28 at the beginning of the stroke is above and inclined at about 45° to the horizontal and during the thrust is caused to pass across the horizontal to a position depending at about 45° to the horizontal. In this way the downward thrust of the operator's foot is economically transmitted into rotary movement of the gear train. As the lever 28 is relatively long compared to the lever 34, it will be apparent that there is a material reducing power transmission afforded by this device and this reducing is further enhanced by making the gear 25 of larger diameter than the gear 23, thus providing a simple compact form of reducing gear set.

By this device the actuator's foot, moving over a relatively long distance (six or seven inches) acts through the reducing gear train

to move the powerfully held gate 12 over a relatively shorter distance to fully open the same. By this means a quick, powerful thrust of the operator's foot upon the pedal 5 quickly opens the cut-cut even against the tension of the powerful holding spring 13. With the thrust member depressed the operator moves his foot laterally thus causing the shoulder 33 to engage under the flange 10 18 to hold the gate in opened position shown in dotted lines in Figure 2.

When it is desired to close the gate the operator simply kicks the depressed head 32 and the spring 13 is then free to react 15 through the mechanism and return the parts to their normal positions.

By means of a device of this character it is possible to install a pedal actuated mechanism for operating against the tension of a 20 heavy spring and to position the same in a small compact space out of the way beneath the floor. The compacted meshed gear train construction illustrated provides a simple form of transmission which can carry the 25 strains incidental to a device of this character without necessitating the use of heavy metal reinforced parts. The device may be quickly installed simply by drilling the part of the floor upon which the control is 30 mounted and making the necessary connection with the throttle lever or other part to be controlled.

While I have shown and described, and have pointed out in the annexed claims, certain novel features of my invention, it will 35 be understood that various omissions, substitutions and changes in the form and details of the device illustrated and in its operation may be made by those skilled in the 40 art without departing from the spirit of the invention.

Having thus described my invention, I claim:—

1. In a device of the class described, the 45 combination of a pair of meshed geared members, a relatively long arm extending radially from one of the gear members to turn the same, a manually actuated thrust member pivotally connected to said arm, means for guiding the thrust member, said arm movable over an arc and across a radial line perpendicular to the line of thrust of said member, and a mechanism control member connected to the other geared member 50 and actuated thereby.

2. In a device of the class described, the 60 combination of a pair of meshed gear members, a relatively long arm extending radially from one of the gear members to turn the same, a manually actuated thrust member pivotally connected to said arm, means for guiding the thrust member, said arm movable over an arm and across a radial line perpendicular to the line of thrust of said 65 member, and a mechanism control member

connected to the other geared member and actuated thereby, said arm and geared members co-acting to form a reducing gear connection between the thrust member and the control member.

3. In a device of the class described, the combination of a pair of meshed geared members, a relatively long arm extending radially from one of the gear members to turn the same, a manually actuated thrust member pivotally connected to said arm, means for guiding the thrust member, said arm movable over an arc and across a radial line perpendicular to the line of thrust of said member, a mechanism control member 70 connected to the other geared member and actuated thereby, and means acting on the thrust member for returning the same to its normal position.

4. In a device of the class described, the combination of a pair of meshed gears co-acting to form a reducing gearing, a thrust member operatively connected to one of said gears to turn the same, means for guiding said member in a line perpendicular to a 80 radius of said gear and a pull member connected to the other gear and operatively connected to be actuated from the turning movement of said other gear.

5. In a device of the class described, the 85 combination of a gear, a thrust member mounted for reciprocatory movement and means pivotally connecting said member with the gear to rotate the same by a thrust on said member, a supporting member, a second gear demountably carried by said support and adapted to be revolved about its axis and set in adjustable meshing engagement with the teeth of the first named gear, and a mechanism control rod connected to said 90 second gear to be actuated by the rotation thereof.

6. In a device of the class described, the combination of a gear, a thrust member mounted for reciprocatory movement and 100 means pivotally connecting said member with the gear to rotate the same by a thrust on said member, a supporting member, a second gear demountably carried by said support and adapted to be revolved about its 110 axis and set in adjustable meshing engagement with the teeth of the first named gear, a mechanism control rod connected to said second gear to be actuated by the rotation thereof, and means for securing said second 115 gear in its adjusted position relative to the first named gear.

7. An article of manufacture constituting a valve control including a supporting bracket provided with means for fastening 120 the same to the underside of a floor and provided with a thrust member-guiding-opening extending therethrough, a gear train mounted on said bracket, a thrust member guided in said opening and operatively con- 125 130

nected to the first member of the gear train for turning the same, and a control rod pivoted to the last member of the gear train.

8. An article of manufacture including a supporting bracket provided with means for fastening the same to the underside of a floor and provided with a thrust member-guiding-opening extending therethrough, a gear train mounted on said bracket, a thrust member guided in said opening, a pin and slot connection between the lower end of the thrust member and the first member of the gear train, and a control rod pivoted to the last member of the gear train.

15 9. In a control mechanism the combination of a pedal, a support therefor constructed to guide the pedal therethrough in a predetermined direction, said pedal having a lateral extension with a slot disposed at an angle to said direction, a member rotatably mounted apart from the line of movement of said pedal extension but having an arm extending towards said pedal and a pin on

said arm near the outer end thereof engaging said slot, whereby movement of said 25 pedal is transmitted to the rotatable member.

10. In a control mechanism the combination of a pedal, a support therefor constructed to guide the pedal in a predetermined direction through said support, said pedal having a lateral extension with a slot disposed at an angle to said direction, a member rotatably mounted apart from the line of movement of said pedal extension but having an arm extending towards the pedal, a pin on 35 said arm near the outer end thereof engaging said slot and resilient means acting on the pedal to maintain the pedal in its normal position.

Signed at New York in the county of 40
Queens and State of New York this 7th day
of November A. D. 1917.
